The ornamental design for a condiment shaker, as shown and described.

DESCRIPTION

FIG. 1 is a top, front perspective view of a condiment shaker showing my new design;

FIG. 2 is a top, rear perspective view thereof;

FIG. 3 is a left side elevational view thereof, the opposite side being identical;

FIG. 4 is a top plan view thereof;

FIG. 5 is a top, front perspective view of an alternate embodiment of FIG. 1;

FIG. 6 is a top, rear perspective view of FIG. 5;

FIG. 7 is a left side elevational view of FIG. 5, the opposite side being identical; and,

FIG. 8 is a top plan view of FIG. 5.

The undisclosed bottom views are unornamented.
